UNITED STATES PATENT OFFICE.

WILLIAM DAW SCALE, OF PINEVILLE, KENTUCKY.

CASH-FARE MANIPULATOR.

Application filed July 14, 1926, Serial No. 122,485 Renewed October 15, 1928.

This invention relates to cash fare manipulators and has for its object a simple, efficient and reliable device for compactly housing a book of tickets and is provided with means for removing neatly, portions of the tickets to indicate the amount of fare paid.

A further object of the invention is the provision of a ticket holder which includes means for permitting the removal of a portion of the ticket, said means also operating to force the stubs out of contact with an unmutilated ticket so that the portion of said ticket may be removed as previously stated, the displacement of the stubs, permitting the last ticket to be readily detached.

This invention will be best understood from a consideration of the following detailed description, in view of the accompanying drawings forming a part of the specification; nevertheless it is to be understood that the invention is not confined to the disclosure, being susceptible of such changes and modifications which shall define no material departure from the salient features of the invention as expressed in the appended claims.

In the drawings:

Figure 1 is a view in perspective of a cash fare receipt manipulator, constructed according to the principles of my invention.

Figure 2 is a longitudinal vertical section of the manipulator,

Figure 3 is a transverse horizontal section taken along the line 3—3 of Figure 2,

Figure 4 is a plan view of one form of receipt employed with the manipulator,

Figure 5 is a plan view of another form of the ticket.

Referring more particularly to the drawings 10 designates a leather casing having a leaf 11 secured to the bottom of a metal housing 12 by means of a separable fastener shown at 13. A second leaf 14 acts as a cover for the front of the housing 12. It will be seen that when the said leaf is in closed position, a very neat and compact book-like form is presented.

The housing 12 has its face adjacent the leaf 14 open while the portion of the housing as indicated at 15 forms the bottom of the same. An end wall 16 has an extension bent inwardly as shown at 17 in spaced relation from the end wall to provide a bearing or track for the inturned ends 18 of a bail 19. The opposite end of the housing is

open and the side walls 20 adjacent the open end are sheared off at an angle as shown at 21 to eliminate sharp edges.

It will be noted that the housing is formed of one piece and the base member 15 has an extension 22 integrally formed therewith and bent inwardly in spaced relation with the bottom 15. The side edges of the extension are bent downwardly as shown at 23 and lugs 24 at the inner end of the extension projecting from the end lugs 23 and inserted through perforations at the bottom 15 with swaged edges securing the extension 22 to the said base member. The inner end 25 of the extension 22 is spaced from the member 17 in order to permit the ready insertion of the back 26 of the book of receipts, the space between the extension 22 and the base 15 providing the housing for said back.

The bail 19 is provided with a pair of spaced arms 27 connected at their outer ends by means of a bridging portion 28. This bridge portion intermediate its ends is curved so that the same will fit neatly against the free ends 29 of the receipts and below the top of the first receipt. A cutter 30 is slidably mounted with bearings 31 at its opposite ends which will receive the arms 27 of the bail. This cutter is provided with a portion 32 adapted to be engaged between the fingers for the convenience of sliding the cutter over the surface of the receipt. The sharp edge 33 is formed on the cutter so that when the free ends 29 of an upper ticket are pulled with sufficient force a ticket will be sheared off by said cutting edge. The opposite edge 34 is enlarged and is adapted to ride over the face of the receipts so that after a portion of a receipt has been removed leaving a stub the cutter may be moved beyond the free edges of the stub and then returned, the enlarged edge 34 engaging the free end of the stub and moving a portion of the same upwardly and away from contact with the unmutilated receipt. By this construction it will be seen that the member 30 not only provides a sharp edge for aiding in removing the tickets but the enlarged edge 34 provides

for the displacement of the stubs so that the next unmutilated ticket or receipt may be snugly engaged by the cutting edge 33 for removing the portion of said receipt as desired. This permits the ready removal of portions of all tickets down to the last receipt.

It will be noted that the bail is not only

pivottally mounted between the end wall 16 and the in-bent portion 17 but the bail is also slidably mounted so that the in-bent portion 18 may be moved inwardly towards the bottom 15 as the fare receipts are gradually removed from the book, whereby the cutter 30 may be alway maintained in close contact with an unmutilated fare receipt.

I claim:

- 10 1. A device of the character described comprising a receptacle, having a bottom, side walls, and an end wall, the end wall being provided with an extension bent inwardly in spaced relation with the end wall, a 30 bail of U-shaped construction having its free ends bent inwardly and located between the extension and the end wall so that the bail is not only pivotally mounted but slidably mounted in the container, a cutter having bearings with opposite ends, said bail including legs adapted to receive the bearings, a cutter being provided with a knife at one edge and an enlargement at the opposite
- 15
- 20

edge and means for maintaining a book of fare receipts in the container.

2. A device of the character described comprising a receptacle, having a bottom, side walls, and an end wall, the end wall being provided with an extension bent inwardly in spaced relation with the end wall, a 30 bail of U-shaped construction having its free ends bent inwardly and located between the extension and the end wall so that the bail is not only pivotally mounted but slidably mounted in the container, a cutter having bearings with opposite ends, said bail including legs adapted to receive the bearings, a cutter being provided with a knife at one edge and an enlargement at the opposite edge, the base member being provided with an extension bent inwardly in spaced relation with the bottom of the container to provide a housing to receive the back of the book of fare receipts for maintaining the book against displacement.

WILLIAM DAW SCALF.
